UNITED STATES PATENT OFFICE.

FRANK A. FAHRENWALD, OF CHICAGO HEIGHTS, ILLINOIS.

METALLURGICAL FURNACE.

Application filed October 12, 1925. Serial No. 61,989.

This invention relates to metallurgical furnaces of the type employed for the annealing of steel sheets and the heating or reheating of rods, rails, sheets, skelp, 5 blooms, bars, and other articles during the process of rolling or forging. It has for its objects the provision of a new and improved construction of the furnace and roll whereby such sheets and other finished products 10 can be annealed and the other articles can be heated with greater rapidity, less expense and better physical results than heretofore. Formerly steel sheets were annealed by placing them in piles on suitable supports 15 in a chamber which was afterwards heated and allowed to cool, it being considered impossible to transport the hot sheets. Later attempts were made to pass the sheets through a furnace in a continuous 20 manner but difficulty was experienced in securing satisfactory results, the difficulties experienced being mainly due to contact with the carrying members. These difficulties have been of two natures: first, a failure 25 of the carrying members to reach the annealing temperature has resulted in lack of uniformity in the finished product; and also the surfaces of the sheets were blemished and marred by the supporting members which were either of greater hardness 30 than the steel sheets at the temperature employed or which had hardened accretions built up thereon.

The maximum annealing temperature ever reached by the stationary process was seldom above 1700° Fahrenheit; the maximum temperature reached during the continuous process annealing has seldom heretofore been above 1750°. However, I have 35 discovered that if a temperature of 1900° Fahrenheit can be obtained some very marked advantages are secured, chief among the same being that the quick, sharp heating affords a maximum of softness and the quickness with which the heating takes place 40 also prevents grain growth and therefore results in a fine-grained, easily manipulated product. This high temperature, however, entails certain pronounced difficulties, 45 chiefly concerned with the supporting of the sheets. For example, the sheets must be kept in rapid motion throughout the high temperature zone and I have further discovered that for the best results it is necessary 50 to have the supporting members hotter than the sheets. Heretofore, owing to the necessity of shielding the supporting members, the same were either mounted in a separate chamber having only their engaging portions projecting into the heated space, or elaborate water cooling precautions were employed which in either case so reduced the temperatures of the sheet-engaging portions as to prevent the portions of the steel sheets coming in contact therewith from reaching the same temperature as other portions and hence producing a sheet insufficient in uniformity of texture and one which could not be drawn accurately to shape in dies; and in addition the oxide coating formed upon the sheet as a result of the heating becomes somewhat sticky at the annealing temperatures and is picked up by the colder supports where it forms irregular accretions which at their comparatively low temperature are so hard and sharp as seriously to dent and mar the heat-softened sheets with the result that smoothly finished work was difficult or impossible to obtain.

I have found if the rolls, or particularly the rims thereof, or other engaging members be kept at a temperature at least equal to or preferably above the temperature of the sheets, these drawbacks are entirely overcome. The sheets exhibit a high degree of uniformity in hardness and ductility and in the rare case that any oxide coating collects upon the rolls or rims or other supports it is comparatively soft and non-injurious at this high temperature, but the usual experience is that no such accumulation occurs inasmuch as this material appears to have a greater adhesion to the colder surface than to the warmer surface, with the result that it remains upon the sheet which is the cooler of the two. It should be understood that the rolls are themselves made of a non-corrodible metallic alloy which does not itself oxidize under the conditions of operation and any oxide which may be present is that formed upon the surface of the sheet which is undergoing treatment and is transferred to the roll mechanically during the moment of contact. In fact it is entirely possible by the use of suitable precautions, in combination with the improvements herein described, to effect this annealing in a neutral or reducing atmosphere.

In order to withstand the high tempera-

tures employed in this operation and also to enable successful mounting in bearings I have found it important to make the rolls not only of a high temperature alloy but 5 also of a peculiar shape and construction. In the drawings accompanying and forming a part of this application I have shown certain physical forms in which my inventive idea may be embodied although it 10 will be understood that many other detail forms can be devised and that these drawings are intended rather to illustrate the general features of my invention than to limit me to the details shown. Fig. 1 is 15 a vertical cross sectional view through a furnace embodying my improvements showing one of my improved rolls partly in section and partly in elevation; Fig. 2 is a similar view showing a modified type of roll 20 and bearing; Fig. 3 is a horizontal sectional view through a series of rolls showing a different type of roll; and Fig. 4 illustrates the preferred method of driving the rolls.

The furnace itself preferably comprises a 25 horizontal hearth 1, upright side walls 2—2 and arched roof 3, the walls being embraced by upright steel I-beams 4—4 and longitudinal members, certain of which are indicated at 5, 5, riveted thereto, thereby with 30 the assistance of further framing members, not shown, producing a frame work which supports the thrust of the roof and steadies the side walls.

Secured to the uprights 4—4 are horizontal shelves 6, 6, one at each side of the furnace, on which are mounted the journal boxes 7, 7 in which are mounted the bearing portions 8, 8 of the rolls. Each of these rolls comprises a hollow body portion 10 having a diameter considerably greater than that of the shaft. Preferably this body is cast all in one piece and integral with the portions 8, 8 the latter being preferably hollow as shown in Figs. 1 and 3 although it 15 is possible to make them solid as shown at 8 in Fig. 2. There are numerous advantages in making these bearing portions hollow; the chief advantages being that it reduces the conduction of heat from the furnace interior, and that it facilitates supporting the core during the casting and the breaking out of that core after the casting is effected. The body of the roll also is preferably formed with apertures 12, 12 cored 20 therein. These apertures are best formed in the tapering ends where the body of the roll joins the shaft although they may also be made in the cylindrical portion of the body, particularly in case the exterior of the body be formed with circumferential ribs as indicated at 13 in Fig. 1, in which case some of these apertures may fall between adjacent ribs. These apertures have the combined effect of constituting additional supports for the core and of reducing the weight 25

of the roll without seriously impairing its strength. The apertures in the slanting end portions have the further advantage of cutting down the amount of metal at this point and thereby reducing the cross section of 70 metal available for the conduction of heat to the exterior of the furnace.

The exterior of the roll may either be cylindrical and unbroken as shown in Fig. 3, or cylindrical and apertured as shown in 75 Fig. 2, or ribbed as shown in Fig. 1. Each formation has advantages. The smooth exterior of the rolls in Figs. 2 and 3 affords a larger area of contact for the plates, assuming the plates are sufficiently flat or flexible 80 to lie smoothly, although it is necessary to smooth or grind a larger surface of roll; the use of ribs 13 as shown in Fig. 1 reduces the amount of roll surface necessary to be machined, but likewise reduces the area of 85 possible contact with the sheets.

It is possible to use these rolls either naked as shown in Figs. 2 and 3 and at the right hand side of Fig. 1, or to provide them with circular hoops or rims 15 of suitable alloy 90 secured thereon in any suitable manner as shown at the left hand side of Fig. 1. An advantage of using these enlargements is that the enlargements of adjacent rolls may interfit, thereby enabling a more uniform 95 support of the sheet with a larger space between adjacent rolls. When these rims are used I prefer to employ the ribbed type of roll exterior as shown in Fig. 1.

The bearings may be of numerous types 100 but in any case are preferably made of a rather massive metal construction intimately secured to the shelves, 6, 6, in heat conducting relation. The bearings are best provided with brass bushings 20 as shown in Figs. 1 and 3, although I have had excellent 105 success with bushings of Babbitt metal. In Fig. 2 the bearing comprises a plurality of hollow rollers 17, 17, surrounding the shaft and running in a ring member 18, this arrangement being particularly advantageous 110 when the temperature of the shaft is especially high.

Any suitable or desired expedient may be employed to rotate these rolls but the one 115 I prefer is that shown in Figs. 1, 3, and 4 wherein the end of each shaft is provided with a sheave 21 having a peripheral groove 22 for the reception of a cable 23. This groove is preferably made sufficiently wide 120 to take two turns of cable, and the cable is preferably wrapped around the sheaves so as to exhibit a large area of frictional contact with each. Preferably this cable is wrapped around the sheaves in pairs as 125 shown in Figs. 3 and 4. The cable is kept taut by a suitable idler pulley 24 and moved by a drive pulley 25. The advantage of this cable drive is that it is steady, uniform and very flexible. When gears are used there is 130

- necessarily a small degree of inequality of motion, especially with the rather coarse toothed gears necessarily employed about such a furnace. As a result geared rolls do not all rotate evenly together but differ by minute degrees which tend to produce minute roughnesses on the sheets. By the cable-drive herein described this is overcome.
- 10 The furnace may be heated in any desired manner. Heretofore most installations have employed gas, but my preference is to employ electrical resistors mounted horizontally above and below the rolls as shown at 15 27 and 28 respectively in Fig. 1. By the use of electrical heating and maintaining a slight positive pressure of a reducing atmosphere inside the furnace, combined with certain obvious precautions at the entrance and exit apertures, the annealed plates are delivered bright and polished.
- Even with fuel firing it is customary, however, to maintain a slight positive pressure inside the furnace to prevent entrance of outside air. In order to prevent escape of the hot gases through the roll shafts, which would have the multiple disadvantage of wasting heat from the furnace, overcooling the rolls, and overheating the bearings, the 20 interior of each shaft is closed-off in some manner. When the shaft is made solid as shown in Fig. 2 this takes care of itself, but when the shaft is made hollow as shown in Figs. 1 and 3, the best plan is to close the 25 inner end of the hole with a plug 30 which may be either of metal or of refractory cement. Leakage around the exterior of the shaft is best prevented by a packing of some soft refractory material such as asbestos 30 held in place by a plate 32.
- I do not limit myself to any one alloy although I prefer to use one containing between about 14% and about 18% of chromium together with from about 1/2% to 45 about 2% of silicon and from about 30% to about 38% of a non-ferrous, iron-group metal, the balance consisting chiefly of iron, and the percentage of carbon being preferably kept very small. Such an alloy will 50 readily withstand a temperature as high as 2250° Fahrenheit without deterioration; and most of the compositions within the range indicated are readily machined although this is not highly important to the present design since the rolls can be finished solely by surface grinding which renders many other alloys available for the purpose.
- One advantage of all such alloys for the purpose in view is that their coefficient of 55 heat conductivity is rather small so that their tendency to become overheated at their ends is small, especially when the shafts are made hollow. This fact, coupled with the mounting of the bearings wholly outside the furnace and in heat conducting contact with an external metallic frame work of substantial dissipating area, keeps the temperature of the bearings down so low that I have been able to employ Babbitt metal bearings and lubricating oil without the use of local cooling even with a furnace temperature above 1900° F. In case a lower bearing temperature is desired I introduce into the hollow shaft a small water pipe 35 connected to a header 36. Only a slow drizzle is required 70 in any case and it may be allowed to evaporate entirely; I do not find such water cooling generally necessary since the air cooling of the furnace frame coupled with the heat conductive mounting of the bearings constitutes a sufficient means to dissipate the comparatively small amount of heat which the peculiar construction of the roll allows to reach the bearing portion.
- Rolls of the composition and construction 75 herein described have been operated for a long time at temperatures above 2100° F. without observable deterioration or breakdown of any kind. Owing to the peculiar shape of the rolls and the method of mounting many alloys can be employed which would not exhibit the necessary physical strength in other designs. I have chosen sheet annealing as an example chiefly because this process constitutes a particularly 80 difficult test of any furnace owing to the thinness of the product and the fact that the process must be performed without injury to the surface appearance. It is obvious that the furnace can be used for purpose of heating or reheating sheets, skelps, blooms, bars, rods, rails, plates, etc., before or during rolling and forging operations, and I believe myself to be the first to produce a furnace of this type where the rolls 90 95 are operated at the full furnace temperature, wholly without cooling even up to intense white heats of 2200° F. I do not limit myself to the alloy mentioned nor to any details of design or structure except as specifically recited in my several claims, which I desire may be construed each independently of limitations contained in other claims.
- Having thus described my invention what I claim is:
1. In a metallurgical furnace, a plurality of parallel horizontal one piece rolls traversing the furnace chamber and having coaxial shafts at opposite ends projecting through the furnace walls, each roll being hollow and larger than its shafts, and means for rotating all said rolls in the same direction at the same peripheral speed, said shafts having no passageway therethrough.
2. In a metallurgical furnace, a plurality of parallel, horizontal, metal rolls located in the furnace chamber and having coaxial bearing portions at opposite ends thereof projecting through the furnace walls, a metallic frame work outside the furnace walls,

- bearings for said bearing portions carried by said frame work, said bearings having heat conducting contact with said frame-work, means for rotating all said rolls, and means for preventing the convection of gaseous fluid through or around said bearing portions, said rolls being hollow and having perforations communicating with the interior.
10. 3. In a metallurgical furnace, a furnace body having spaced upright walls, each of which is formed with a horizontal row of spaced tapering apertures, each aperture being larger at its inner end than at its outer end and the apertures in the respective walls being opposite each other, a plurality of parallel, horizontal, metal rolls traversing the furnace chamber and having their ends located in the larger parts of said apertures, each of said rolls having at each end a coaxial rigid shaft of smaller diameter than the roll body, said shafts projecting through the smaller parts of said apertures, and means outside the furnace walls for supporting and driving said rolls, the body portion of each roll being externally cylindrical and internally hollow and having perforations between said shafts.
4. In a metallurgical furnace, a furnace body having spaced upright walls, each of which is formed with a horizontal row of spaced apertures, each aperture in one wall being opposite an aperture in the other wall and having its inner end of larger diameter than its outer end, a plurality of parallel, horizontal, hollow, perforated metal rolls traversing the furnace chamber, each of said rolls having at each end a hollow, integral, coaxial shaft of smaller diameter than the roll itself and merging therewith by way of a flared portion, and bearings for said shafts outside the furnace wall, each roll having its flared portions confined substantially within the limits of the furnace walls.
45. 5. In a metallurgical furnace, a plurality of parallel horizontal, one piece metal rolls traversing the furnace body from side to side, the ends of said rolls being of reduced diameter to form shafts and the body thereof inside the furnace being of enlarged size to constitute the roll proper, bearings for the shafts located outside of and spaced from the furnace walls, and means for cooling the exposed portions locally, the walls of the roll being thin whereby conduction of heat to said shafts is reduced, and perforated whereby temperature equalization is facilitated.
60. 6. In a metallurgical furnace, a plurality of parallel, horizontal, hollow metal rolls, each roll having a bearing portion extending outside of said furnace, bearings for said rolls located outside of said furnace, means for heating that portion of the interior of each roll which lies inside the furnace to the full furnace temperature, and means for preventing the flow of such heat by fluid convection toward either end of said roll.
7. In a heat-treating furnace, the combination with a plurality of parallel horizontal hollow cylindrical perforated rolls adapted to convey the material, each roll being made of metal and integral from end to end, the end portions being of reduced size to constitute bearing portions, of bearings for said bearing portions, and means for cooling said bearings locally, the cross sectional area of the metal being reduced adjacent to each end of said roll so as to restrict the rate of heat flow from the body of the roll to said bearing portions.
8. In a furnace, a plurality of parallel, horizontal, hollow, metal rolls having integral cylindrical bearing portions at their ends, each roll having its bearing portions located outside of the furnace, and means for preventing fluid movement between such bearing portions and the hollow bodies of said rolls, while permitting fluid movement between the interiors of said bodies and the furnace interior.
9. A roll for a heat-treating furnace comprising a hollow cast metal body having reduced integral coaxial end portions constituting bearing shafts, and also having perforations between said shafts.
10. A roll for a heat-treating furnace comprising a hollow cast metal body having reduced integral coaxial hollow end portions constituting bearing shafts, and also having perforations between said shafts.
11. A roll for a heat-treating furnace comprising a hollow metal body having reduced integral coaxial hollow end portions constituting bearing shafts and plugs in the inner ends of said shafts.
12. A roll for a heat-treating furnace comprising a hollow, substantially cylindrical, metal body having at each end a hollow portion of gradually decreasing diameter which is formed with apertures, and an integral coaxial shaft at each end with which such tapering portion merges.
13. A roll for a heat-treating furnace comprising a hollow, substantially cylindrical, metal body having a plurality of apertures therein, and also having at each end a tapering hollow integral portion which merges into a coaxial shaft.
14. A roll for a heat treating furnace consisting of an integral casting hollow from end to end and concentric to a single axis, the end portions constituting shafts, the middle portion being of increased diameter and constituting the roll body, and the intermediate portions being tapered, said body having apertures therein.
15. A roll for furnaces comprising a hollow body of high temperature alloy having terminals of reduced size constituting bear-

ings, and closures between each bearing and the chamber defined within such hollow body whereby flow and convection of fluid is prevented.

5 16. A roll for furnaces comprising a hollow body of high temperature alloy having hollow axial terminals of reduced size constituting bearings, and means preventing passage of fluid between the interior of said 10 body and the interiors of said bearings.

17. A cast metal roll which is made of high temperature alloy and hollow from end to end, its intermediate portion being larger than its end portions and its inner surface 15 being everywhere substantially parallel to its external surface whereby its thickness is everywhere substantially uniform, and means preventing fluid communication between the larger and smaller portions of the 20 roll interior.

18. In a furnace of the character de-

scribed, a plurality of non-cooled rolls of metal operatively mounted therein, said rolls having hollow bodies and hollow ends, the interior of said bodies being in communication with the furnace interior but not in communication with the interior of such ends. 25

19. In a furnace of the character described, non-cooled rolls of metal operatively 30 mounted therein, said rolls having hollow, thin walled bodies traversing the furnace interior and having cylindrical bearing portions of reduced cross sectional area extending through and journaled outside of the 35 furnace walls, and means preventing gas convection between portions which are inside and outside said furnace.

In testimony whereof I hereunto affix my signature.

FRANK A. FAHRENWALD.
